UNITED STATES PATENT OFFICE.

BENJMAN F. WILLIAMS AND JAMES W. MAYFIELD, OF BLUFFDALE, TEXAS.

DRILL-SUPPORT.

1,161,097.

Specification of Letters Patent. Patented Nov. 23, 1915.

Application filed January 14, 1915. Serial No. 2,210.

To all whom it may concern:

Be it known that we, BENJMAN F. WILLIAMS and JAMES W. MAYFIELD, citizens of the United States, residing at Bluffdale, in the county of Erath and State of Texas, have invented certain new and useful Improvements in Drill-Supports, of which the following is a specification.

This invention relates to drilling apparatus, and more particularly to an apparatus of this character for use in coal or other mines for boring or drilling holes for blasting charges and other purposes.

An object of the invention is to provide an improved post or frame having recesses cut in either side thereof so that the drill-carrying boxing can be operated from either side of the post or frame.

Another object is to provide the frame with detachable jackscrew boxings so that in the event of breakage of the screw or boxing the same may be replaced with a minimum time and labor.

A further object is to provide an improved boxing for the thread bar of the drill.

With these and other objects in view the invention consists in the novel features of construction, combination and arrangement of parts as will be hereinafter more fully described, illustrated in the accompanying drawing and claimed.

In the drawings: Figure 1 is a front elevation of the improved drill frame. Fig. 2 is a vertical sectional view. Fig. 3 is a detail perspective view of the thread-bar boxing. Fig. 4 is a perspective view of the drill, and Fig. 5 is a detail sectional view showing the means for holding one of the jack screw castings to the frame.

Referring to the drawings by numerals, we have shown a flat piece of material bent to form a substantially rectangularly shaped frame having side walls 2 and upper and lower curved walls 3 and 4, respectively.

Intermediate brace members 5 and 6 being secured between the side walls and adjacent the upper and lower walls of the frame by means of bolts 7. The outer edges of either side of the frames are provided with recesses 8 which are alined with respect to the adjacent edges of the frame and are staggered with respect to each other.

Substantially frusto-conically shaped castings 9 and 10 are supported by the respective upper and lower walls of the frame and the intermediate members 5 and 6, the

upper casting 9 having a central bore in which is slidably mounted a pivot member 10. Means for allowing frictional adjustment of the member 10 includes a thumb screw 12, the threaded portion of which extends through the support 13, the latter being rigidly secured between the upper wall member of the casing and the respective brace member. The thumb screw 12 further extends through an opening in the side of the casting 9 whereby manipulation thereof will cause frictional engagement between the member 10 and the inner walls of the casting 9 in order that the said member may be held rigid at different adjusted positions.

The lower casting 10' is positioned within the frame in a manner substantially the same as the upper casting and is held secure to the same through the medium of a washer 14. A pair of slit arms 15 for engagement with the recesses formed in the sides of the casting 10' are carried upon the washer 14, which in conjunction with a pin 16 prevents the accidental displacement of the casting 10' during the operation of my device. The pin 16 passes through alined openings in the lower wall 4, washer 14 and brace member 6, its upper end terminating into a bent portion whereby it is normally held in position.

The casting 10' has an internally screw threaded bore into which is received the upper end of a jack screw 17, a lever 18 of the usual construction being provided upon the latter in order that it may be turned in either direction as desired.

From the foregoing disclosure it is apparent that through the manipulation of the members 10 and 17 the frame portion of the device can be adjusted to conform with certain conditions during the use thereof.

A boxing for the thread bar 19 of the drill 19' is provided which comprises a pair of hinged upper and lower members 20 and 21, respectively, the respective members having lugs formed on one face thereof and having a pin passed therethrough for hingedly connecting the same, the said members being held in a closed engaging position upon the bar 19 by means of a latch 22 which is pivoted to a lug 23, formed on the lower member 21, and which is adapted to engage a lug 24 formed upon the upper member 20. Trunnions 25 being formed on the lug 23 and on one of the hinged lugs in order to support the boxing in any of the alined recesses 8.

From the foregoing description taken in connection with the accompanying drawings, it is thought that the construction and operation of the device will be clearly understood, and while we have herein shown and described one specific form of our invention, we do not wish to be limited thereto except for such limitations as the claims may import.

10. We claim:

1. A drill post including a rectangular frame, brace members fixed within said frame and spaced from the upper and lower ends thereof, the ends of said frame provided with openings, said brace members provided with smaller openings, in coaxial alignment with the aforesaid openings, conical-shaped castings with their conical portions seated in said openings, the inclined faces of said conical castings bearing against both the end portions of said frame and against said brace members.

2. A drill post including a rectangular frame and spaced from the upper and lower ends thereof, the ends of said frame provided with openings, said brace members provided with smaller openings in coaxial alignment with the aforesaid openings, conical-shaped castings with their conical por-

tions seated in said openings, the inclined faces of said conical castings bearing against both the end portions of said frame and against said brace members, means to retain said castings, and means co-acting with one of said castings to adjust said frame, as and for the purpose specified.

3. A drill post including a rectangular frame, brace members fixed within said frame and spaced adjacent the respective upper and lower ends thereof, a casting extending through the upper end of said frame and the upper one of said brace members, a member adjustable in said casting, a member fixed between the upper end of said frame and the upper end of said brace members and an adjustable member extending through said fixed member and projecting into said casting for retaining said first mentioned adjustable member, for the purpose specified.

In testimony whereof we affix our signatures in presence of two witnesses.

BENJMAN F. WILLIAMS.
JAMES W. MAYFIELD.
